CIRCULAR LOOM

Constantine A. Caldes, Jersey City, N. J.

Application December 16, 1944, Serial No. 568,481

14 Claims. (Cl. 139—15)

1

This invention relates to circular looms and has especial reference to novel shuttle driving means and means for separating the warp for the passage of the shuttles through the shed.

The principal object of the invention is the provision of improvements in a circular loom whereby the production of such loom is materially increased.

Another object of the invention is to simplify the construction and the mode of operation of certain features of a circular loom in order to reduce original and maintenance costs.

With the foregoing and other objects in view, the invention resides in the combination, construction and operation of the parts hereinafter described and illustrated in the accompanying drawings, in which—

Fig. 1 is a fragmentary horizontal sectional view of a circular loom embodying the features of the present invention, the section being taken approximately on the line 1—1 of Fig. 2.

Fig. 2 is a fragmentary vertical sectional view.

Fig. 3 is a top plan view of the power transmitting rotor of the shuttle driving mechanism.

Fig. 4 is a diagrammatic view illustrating the sequence of operation of the shuttles.

Fig. 5 is a perspective view of one of the shuttle driving members.

Fig. 6 is a perspective view of a warp thread shifter.

The features of the present invention may be incorporated in circular looms of various types. Only so much of a loom has been shown for a clear understanding of the invention.

On reference to Figs. 1 and 2, it will be apparent the loom includes a shuttle driving rotor 10 having a central hub 11 which is journaled on a central hollow shaft 12 fixedly secured, as at 13, to the bed 14 of the loom frame 15. A bevel gear 16 fast on the hub 11 meshes with a bevel gear 17 fast on one end of a horizontal shaft 18 supported by bearings 19 and 20, respectively, on the bed 14. The shaft 18 transmits power from a suitable source to the rotor 10 through the intervention of the gears 16 and 17.

The upper end of the shaft 12 has an upstanding core 21 about which the woven tubular material is to be formed to pass upwardly through the tube 22 disposed coaxially with respect to the core 21. The tube 22 is fixed on a spider 23 mounted on top of a drum 24 in which the shuttles 25 travel in a circular path.

The drum 24 is fixedly supported in any suitable manner on the upstanding flange 26 on

the bed 14. The drum 24 has a suitable number of vertical slots 27 through which the warp threads 28 extend to the weaving point. It is to be understood the warp threads 28 are guided from creels and are acted on by tensioning means. The warp threads 28 are disposed radially as indicated in Fig. 1 in dot and dash lines.

In the present instance there are shown four shuttles 25 which are disposed in such relation with respect to each other that a proper weaving action may take place in which single alternate warp threads 28 are shifted to open the shed for the passage of the weft threads therethrough. Each shuttle 25 includes a frame 29 having an opening therein to accommodate a spool 30 of weft thread 31. The spool 30 is operatively mounted on the frame 29 to keep its thread under proper tension and said thread 31 passes through a guide eye 32 on a horizontal or lateral extension 33 on the frame 29. The weft thread 31 passes from the eye 32 to the weaving point at the core 21. The shuttle 25 may be of any preferred type, but in accordance with the present invention will have a lateral extension, such as the extension 33, or equivalent means, which cooperates with means carried around by the rotor for the purpose of driving the shuttle, and at the same time enabling the passage of the lower warp threads of the open shed between the shuttle and the rotor. The frame 29 has a point 34 on its leading end, and a shoe 35 which slides in a circular passageway formed in the drum 24.

The shuttle driving mechanism in addition to the rotor 10, includes driving members 36, there being three of such members 36 used in conjunction with each shuttle 25 in the present instance. As shown most clearly in Fig. 5, each driving member 36 consists of a bar of metal of suitable length and rectangular in cross-section. The upper end 37 of the member 36 is preferably round in cross-section. A cam roller 38 is mounted on the member 36 at one side midway between the ends thereof. The driving members 36 are disposed in notches 39, respectively, in the periphery of the rotor 10. The extension 33 has holes 40 therein to receive the upper ends 37, respectively, of the related group of three driving members 36. These driving members 36 are disposed vertically by reason of the notches 39 adjacent a stator 41 consisting of a ring having an undulated or hill and dale groove 42 providing upper and lower cam surfaces 43 which act on the rollers 38 while disposed in said groove 42. The provision and arrangement of parts is such that at least one of the driving members 36 will be en-

gaged with the extension 33 at all times to impart a driving effort. At times two of the members 36 are engaged with the extension while the third member 36 is disengaged, and vice versa. Each driving member 36 is moved up and down by reason of its roller 38 and the cam surfaces 43 plus the rotatory movement of the rotor 10. Each of the driving members 36 of each group moves down to allow each lower warp thread 28 to clear or pass between the shuttle and the rotor, and then said member 36 moves up into engagement with the shuttle extension 33 for imparting a driving effort to the shuttle. In this manner each shuttle 25 is constantly driven around in a circular path.

The warp threads 28 normally lie horizontally in a plane slightly below the point 34 of each shuttle 25 as shown in Fig. 4. In order to shift alternate warp threads 28 upwardly from the normal position, there is provided shifting means as follows. A shifting member 44 is arranged in cooperative relation to the point 34 of each shuttle 25. The member 44 consists of a bar of metal of suitable length and is rectangular or non-circular in cross-section. The upper end portion of the member is enlarged somewhat and has an oblique or inclined surface 45. A cam roller 46 is mounted on one side of the member 44 midway between the ends thereof. The shifting member 44 is disposed to move up and down in a notch 47 in the rotor 10 at the periphery. The roller 46 is disposed to travel in the groove 42 to be acted on by the cam surfaces 43. These surfaces 43 in cooperation with the rotatory movement of the rotor 10 move the member 44 upwardly which causes the surface 45 to act on the particular warp thread 28 and to shift the thread upwardly out of its normal position to be engaged by the upper inclined surface of the point 34. The shifting member 44 then immediately moves downwardly into its down position clear of the next warp thread lying in its normal position. The point 34 carries each upwardly shifted warp thread further to a maximum degree, while alternate warp threads are shifted downwardly to open a shed for the passage of the weft thread 31 therethrough.

From the foregoing it will be understood the weft threads of the shuttles are interwoven under one warp thread and over another in succession for the weaving operation. The use of a plurality of shuttles increases the speed of the weaving operation and so increases the production of the loom. Any suitable number of shuttles may be used according to the design of the loom. Also, the order in which the warp threads are shifted may be varied by changing the number and relative disposition of the shuttles.

I claim:

1. In a circular loom, a shuttle, a stator to guide the shuttle, a rotor, shuttle driving members arranged on said rotor in relation to said shuttle for movement into and out of engagement with the shuttle while traveling with said rotor to drive the shuttle and enabling warp threads to pass between the shuttle and the rotor, and means to operate the driving members.

2. In a circular loom as set forth in claim 1, wherein said driving members move up and down with respect to the rotor.

3. In a circular loom as set forth in claim 1, wherein said last means includes cam surfaces on said stator.

4. In a circular loom as set forth in claim 1, wherein said last means consists of cam surfaces

on said stator and rollers on said driving members respectively which cooperate with said cam surfaces.

5. In a circular loom as set forth in claim 1, and means carried by the rotor which is operated by means on the stator to cooperate with the shuttle to open a shed for the weft thread of the shuttle.

10 6. In a circular loom, a shuttle having guided movement in a circular path, and driving members each movable into and out of engagement with said shuttle, said shuttle having holes therein to receive the driving members respectively for the aforesaid purpose, each of said driving members when engaged with said shuttle imparting a driving effort thereto along its circular path.

15 7. In a circular loom, a rotor, a ring stator surrounding said rotor, a shuttle having guided movement in a circular path, driving members arranged in peripheral notches respectively in said rotor and contacting said stator so that said driving members may move up and down while traveling around with said rotor, and coacting means on said driving members and the stator to cause the up and down movement of said driving members in succession, each of said driving members when moved up engaging said shuttle to impart a driving effort from the rotor to the shuttle.

20 8. In a circular loom, a rotor, a shuttle having guided movement in a circular path with respect to the axis of said rotor, a stator, said shuttle having spaced holes therein, driving members, and coacting means on the rotor, stator and driving members to operate the driving members to cause them to severally enter said holes to drive the shuttle along its circular path in response to the rotation of said rotor.

25 9. In a circular loom, a rotor, a ring stator surrounding said rotor, said stator having a continuous groove therein providing upper and lower complementary cam surface, a shuttle having guided movement in a circular path with respect to the axis of said rotor, driving members disposed vertically in peripheral notches respectively in said rotor and contacting said stator, each of said driving members having a cam roller disposed in said groove to cooperate with said cam surfaces, the provision and arrangement being such that the driving members move up and down in succession while traveling around with the rotor, and each of said driving members in its up position engaging said shuttle to impart a driving effort from the rotor to the shuttle, and each driving member in its down position in turn enabling each lower warp thread to pass between the shuttle and the rotor.

30 10. In a circular loom as set forth in claim 9, a warp thread shifter for lifting alternate warp threads to the action of shed opening means on the shuttle, and coacting means on the rotor and stator to operate the warp thread shifter in timed accord with the movement of the shuttle.

35 11. In a circular loom, a rotor, a shuttle having guided movement in a circular path with respect to the axis of said rotor, a stator, a warp thread shifter, and coacting means on the rotor, stator and shifter to operate the shifter at predetermined intervals in response to the rotation of said rotor, said warp thread shifter moving up and down at said intervals while traveling around with said rotor.

40 12. In a circular loom, a rotor, a shuttle having guided movement in a circular path with respect to the axis of said rotor, a stator, a warp thread shifter, and coacting means on the rotor,

stator and shifter to operate the shifter at predetermined intervals in response to the rotation of said rotor, said warp thread shifter consisting of an elongated member non-circular in cross section and having an inclined surface on its upper end, and said shifter moving up and down at said intervals while traveling around with said rotor.

13. In a circular loom, a rotor having a guide groove therein, a shuttle having guided movement in a circular path with respect to the axis of said rotor, a warp thread lifter operatively mounted in said groove to travel with the rotor in relation to the shuttle, and means for moving the warp thread lifter up and down at predeter-

10 mined intervals in response to the rotation of said rotor.

14. In a circular loom, a rotor having a guide groove therein, a shuttle having guided movement in a circular path with respect to the axis of said rotor and which travels in unison with the rotor, a warp thread lifter in said groove having up and down movement in relation to the shuttle and which is caused by the rotor to travel therewith, and means to cause the up and down movement of the warp thread lifter at predetermined intervals while traveling around with said rotor.
